CLAIM

The ornamental design for a set of connectors for a modular cable protector, as shown and described.

DESCRIPTION

FIG. 1 is a top axonometric view of a set of connectors for a modular cable protector of my new design.

FIG. 2 is a top axonometric view of a male connector thereof, shown separately and enlarged for ease of illustration.

FIG. 3 is a top plan view thereof.

FIG. 4 is a bottom plan view thereof.

FIG. 5 is a left side elevational view thereof.

FIG. 6 is a right side elevational view thereof.

FIG. 7 is a front elevational view thereof.

FIG. 8 is a top axonometric view of a female connector of the set, shown separately and enlarged for ease of illustration.

FIG. 9 is a top plan view thereof.

FIG. 10 is a bottom plan view thereof.

FIG. 11 is a left side elevational view thereof.

FIG. 12 is a right side sectional view thereof taken at line 12-12 on FIG. 9.

FIG. 13 is a front elevational view thereof.

FIG. 14 is a top plan view of the set of connectors for a modular cable protector, shown in use; and,

FIG. 15 is a bottom plan view thereof.

The broken lines show portions of the modular cable protector that form no part of the claimed design.

1 Claim, 15 Drawing Sheets
